UNITED STATES PATENT OFFICE.

LARS MULDRUP LANDING, OF GLENWOOD, MINNESOTA.

PERSONAL-ACCOUNT FILE-CASE.

SPECIFICATION forming part of Letters Patent No. 714,715, dated December 2, 1902.

Application filed March 13, 1902. Serial No. 98,085. (No model.)

To all whom it may concern:

Be it known that I, LARS MULDRUP LANDING, of Glenwood, in the county of Pope, State of Minnesota, have invented certain Improvements in Personal-Account File-Cases, of which the following is a specification.

This invention relates to improvements in file-cases; and the object I have in view is to provide a simple, neat, and inexpensive case in which a large number of personal or individual accounts can be filed and in which said accounts will be conveniently held when the case is closed and will be in convenient position for inspection and removal when the case is open.

My invention consists generally in a file-case embodying the constructions and combinations hereinafter described, and particularly pointed out in the claims.

In the accompanying drawings, forming part of this specification, Figure 1 is a longitudinal section of my improved file-case, the same being shown partly in perspective and the case being represented as closed. Fig. 2 is a similar view showing the case open.

In the drawings, 2 represents the body of the case, which may be of any suitable size and construction and formed of any suitable material. It is preferably of rectangular form and usually constructed of a size to allow it to be conveniently handled and readily placed in one of the compartments of a safe. The case is preferably provided with a vertical slot 3 in its rear end, and the cover 5 is hinged to the body of the case at one end and at or near the bottom of the case by a suitable hinge 7. This cover is of greater depth at the hinged end than at the free end, the sides being formed on an angle or on a diagonal line, as shown in Fig. 2 and as indicated by the dotted lines in Fig. 1. This cover is also provided with a follower 9, preferably of triangular form, as shown in Figs. 1 and 2 of the drawings, and this follower is adapted to project into the body of the case through the slot 3 when the cover is closed, thus bringing it into the position represented in Fig. 1 of the drawings. Arranged within the casing is a loose follower-plate 11, provided with an inclined flange 13. The case is preferably provided with a series of account-covers 15

and with suitable index-cards 17. These covers are preferably those shown and described in Letters Patent No. 685,151, issued to me October 22, 1901, and the case is preferably used for filing the accounts entered on the manifold sheets of the sales-book shown and described in my said patent. I do not, however, limit myself to the use of the file-case for these particular covers and accounts, 55 for the same may be used for the purpose of filing any other accounts. When the case is closed, the follower 9 passes through the opening 3 in the end of the file-case and coming in contact with the follower-plate 11 60 moves said plate against the series of covers or accounts arranged within the case and holds them in an upright position, turning the follower-plate 11 from the inclined position shown in Fig. 2 to the upright position 65 shown in Fig. 1. The file-case may now be handled without danger of disarranging the order of the accounts and may be conveniently placed in a safe, either resting upon the bottom of the case or upon the end or side, according to whichever position may be the most 70 convenient.

In using the case it will ordinarily be placed on a desk or table and the cover turned back to the position shown in Fig. 2, the end 80 of the cover then coming into a horizontal position substantially in line with the bottom of the case. The follower-plate 11 will now tip back into the inclined position, (shown in Fig. 2,) and the covers or accounts and index-cards will assume a similar position, affording convenient access to them and permitting them to be readily removed or inserted.

I do not limit myself to the details of the construction herein shown and described, as the same may be varied in some particulars without departing from my invention.

I make no claims in this application to file-cases having the cover hinged to one end of 95 the case at or near the bottom and having the inclined sides, as I have claimed the same in a separate application of even date herewith, Serial No. 98,086.

I claim as my invention—
1. The combination, with a suitable filing-case, provided with a slot in its end, of a

cover hinged to the case at or near the bottom of the slotted end, and provided with a follower adapted to project through said slot into the case as the cover is closed, substantially as described.

2. The combination, with a filing-case, provided with an open top and with a slotted end, of a cover hinged to the slotted end of the case at or near the bottom thereof, and adapted, when closed, to cover said slotted end, and a follower secured upon said cover and adapted to project through said slotted end.

3. The combination, with a filing-case, provided with an open top and with a slotted end, of a series of account-covers and index-cards arranged within said casing, a cover hinged to the slotted end of the case at or near the bottom thereof, and adapted, when closed, to cover said slotted end, and a follower secured upon the cover and adapted to project through said slotted end, substantially as described.

4. The combination, with a filing-case, having an open top and a slotted end, of a follower-plate arranged within said case, a cover hinged to the slotted end of the case at or near the bottom thereof, and adapted, when the cover is closed, to project through said

slotted end and engage said follower-plate, substantially as described.

5. The combination, with a filing-case, provided with an open top and a slotted end, of a series of account-covers arranged within said case, a follower-plate also arranged with- 35 in said case, a cover hinged to said case at or near the bottom at the slotted end, and provided with a follower adapted, when the case is closed, to project through the slotted end of the case into engagement with said fol- 40 lower-plate.

6. The combination, with a filing-case, having an open top and a slotted end, of a series of account-covers and index-cards arranged within said case, a follower-plate provided 45 with an inclined flange 13, a cover hinged to the case at or near the bottom of the slotted end, and provided with a follower adapted to project through the slotted end of the case, when the cover is closed, into engagement 50 with said follower-plate, substantially as described.

In witness whereof I have hereunto set my hand this 10th day of March, 1902.

LARS MULDRUP LANDING.

In presence of—

A. C. PAUL,
C. G. HANSON.
